US00D812001S

(12) **United States Design Patent** (10) **Patent No.:** **US D812,001 S**
Marcoz (45) **Date of Patent:** **** Mar. 6, 2018**

(54) **CURRENT TRANSDUCER**

(71) Applicant: **LEM Intellectual Property SA**,
 Fribourg (CH)
 (72) Inventor: **Benjamin Marcoz**, Beaumont (FR)
 (73) Assignee: **LEM INTELLECTUAL PROPERTY**
 SA, Fribourg (CH)

(**) Term: **14 Years**

(21) Appl. No.: **29/516,496**

(22) Filed: **Feb. 3, 2015**

(30) **Foreign Application Priority Data**

Aug. 27, 2014 (WO) 835662601
 (51) LOC (11) Cl. 13-02
 (52) U.S. Cl. ..... USPC D13/110

(57) **CLAIM**

The ornamental design for a current transducer, as shown and described.

DESCRIPTION

FIG. 1 is a top front perspective view of a first embodiment of a current transducer showing my new design;
 FIG. 2 is a bottom rear perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof; and
 FIG. 8 is a bottom plan view thereof.
 FIG. 9 is a top front perspective view of a second embodiment of a current transducer showing my new design;
 FIG. 10 is a bottom rear perspective view thereof;
 FIG. 11 is a front view thereof;
 FIG. 12 is a rear view thereof;
 FIG. 13 is a left side view thereof;
 FIG. 14 is a right side view thereof;
 FIG. 15 is a top plan view thereof; and
 FIG. 16 is a bottom plan view thereof.
 The broken lines depict environmental subject matter only and form no part of the claimed design.

1 Claim, 13 Drawing Sheets
